O. Henry Edwards
ATTORNEY

UNITED STATES PATENT OFFICE

WILLIAM A. ZEIDLER, OF BRONXVILLE, NEW YORK

SCISSORS

Application filed May 28, 1929. Serial No. 366,564.

The object of my invention is to provide flat scissors, i. e., scissors where one blade is close against another, and yet these blades, when functioning, will function true and right at all times. This object is accomplished by my invention one embodiment of which is hereinafter more particularly set forth.

For a more detailed description of my invention, reference is to be had to the accompanying drawings, forming a part hereof, in which

Figure 1 is a plan view of a portion of scissors embodying my invention, the scissors being open.

Figure 2 is a similar view of the scissors, closed; and

Figure 3 is a sectional view taken on the line 3—3 of Figure 2.

Throughout the various views of the drawings, similar reference characters designate similar parts.

My improved scissors 1 have a rigid blade 2, and a blade 3 which has a double pivoting and is therefore movable in a peculiar sense which will be described below. The two blades are united at off-set pivot 4 which will now be described. The blade 2 has a laterally extending projection 5 and to this is pivoted a disc 6 which is fixed to the screw 4 and the screw 4 turns in the projection 5 as indicated in Figure 3. The disc 6 is fixed to the laterally extending screw 7, as shown, and to this is secured the blade 3 which has a screw threaded opening to receive the screw 7 and which is not tight on the screw 7 but can turn a little so that the cutting edge 8 of the blade 3 will naturally and instinctively be cutting in proper relation with the cutting edge 9 of the blade 2 of the scissors when used in the conventional manner. The scissors are assembled by securing the parts 6 and 3 together by means of the screw 7 and thereafter connecting the blades 2 and 3 by means of the screw 4. When assembled, the scissors are used in the normal way, but these scissors differ from normal ones because the blades 2 and 3, in their cutting portions, rest flat against each other, and cut accordingly so that it is easier to grind these blades and keep them true and in proper functioning condition.

While I have shown and described one embodiment of my invention, it is obvious that it is not restricted thereto, but that it is broad enough to cover all structures that come within the scope of the annexed claims.

Having thus described my invention, what I claim is:

1. A pair of scissors having two blades, one of which is rigid throughout and provided with an off-set pivot and the other of which has a correspondingly off-set pivot and an additional pivotal connection to its off-set pivot.
2. A pair of scissors having two flat blades, one of which is rigid throughout and provided with an off-set pivot and the other of which has a correspondingly off-set pivot and an additional pivotal connection to its off-set pivot.

In testimony whereof, I have hereunto set my hand this 25th day of May, 1929.

WILLIAM A. ZEIDLER.
